UNITED STATES PATENT OFFICE.

CHARLES F. BUENTE, OF PITTSBURG, PENNSYLVANIA.

FIREPROOF FLOOR CONSTRUCTION.

SPECIFICATION forming part of Letters Patent No. 663,060, dated December 4, 1900.

Application filed January 6, 1900. Serial No. 589. (No model.)

To all whom it may concern:

Be it known that I, CHARLES F. BUENTE, of Pittsburgh, in the county of Allegheny and State of Pennsylvania, have invented a new 5 and useful Improvement in Fireproof Floor Construction, of which the following is a full, clear, and exact description.

The object of my invention is to provide a fireproof floor construction which shall obviate the disadvantages pertaining to constructions heretofore used.

In particular my improvement affords advantages of great strength and ease of construction, cheapness, and relative lightness, 15 and enhanced fireproof qualities.

In the accompanying drawings, Figure 1 shows in vertical section, at right angles to the floor-beams, a floor constructed in accordance with my invention. Fig. 2 is a view 20 on a larger scale, being a section on the line II II of Fig. 1, parallel with the floor-beams and showing three of the tile arches, Fig. 1 being a longitudinal section along one of the arches. Fig. 3 is a view similar to Fig. 2, 25 but showing a modified construction.

As shown in Figs. 1 and 2, the floor is constructed of series of arches arranged at right angles to the floor-beams A and composed of hollow tile centers B B, set permanently in 30 the floor with intermediate bodies of concrete C and overlaid with concrete C', the suspension or tension rods D being arranged in the concrete between the tile centers and being maintained in tension. The bases of the tile 35 centers are in substantially the same horizontal plane and constitute the ceiling, the ceiling-pieces E, as shown in Figs. 1 and 2, being sections of tiles set at the base of the hollow centers B, held in place by cement 40 and formed, preferably, with flanges e. As shown in Fig. 2, the tile centers are composed of upright U-shaped legs F, each leg constituting the side of one of the centers and the top plate G extending from one piece F to the 45 other, the ceiling-pieces E being interposed at the base, as above explained.

In constructing the floor I first form a temporary removable floor of boards, which occupies the position H in Fig. 2. I then lay the 50 tile centers B B, as shown in Fig. 2, upon the boards and then fill in the concrete above and between the centers and apply the usual

wooden sleepers J. When the concrete has set and the floor is finished, the centers remain permanently in the floor, and there is nothing 55 to remove from within them. All that remains to do is to strip off the temporary floor of boards and apply the ceiling-plaster. The upright pillars of concrete between the centers rest at the bottom on tile-supports 60 constituted by the bases of the legs F.

In Fig. 3 I show a modified construction of my invention adapted especially for floorings of small thickness, though it may be used for floors of any dimensions. In such case I may 65 make the tile centers of quadrangular pieces of tile B' B'', each of which may be made in a single piece. Pairs of these centers may be set in close contact and separate from the next tile centers by flanges b, which constitute the base of the concrete pillars. Otherwise the construction is as above explained, 70 concrete being applied above and between the centers and the parts being built in the manner already described. With the construction shown in Fig. 3 separate ceiling-pieces E are not necessary, because they are constituted 75 by the bases of the sections B' B''.

In addition to saving the great cost of removing the wooden centers heretofore commonly employed in floor constructions and enabling the floor to be built at one operation I derive other important advantages from the use of a tile center which remains in the floor as a permanent part of the structure, for becoming integrally united with the concrete the tile adds strength and makes it possible to construct the floor with less thickness and weight of concrete than would otherwise be necessary. The materials of my floor are disposed to the best advantage. The tile, being a better fireproofing material than concrete, 80 is placed where it is nearest the heat in case there should be fire in the building and by protecting the concrete enables me to obtain 85 a given degree of safety against fire with the use of concrete of less expensive grade than heretofore. The concrete, also affording in its mass the greater strength, is disposed in the manner to give the most stability to the 90 floor. The construction is very strong, because the tension-rods D maintain the floor by tension, while the arches of concrete and the centers are in compression. 95

Within the scope of my invention modifications may be made in the form and construction of the parts. For example, the form of the tile centers may be changed, and instead of using suspension rods of the character shown I may employ other tension-rods for suspending or supporting the floor. The tile may be made of other refractory material than earthenware. The tops of the arch-10 centers may be curved or flat, as desired.

I claim—

1. In fireproof floor construction, an arch composed of concrete containing hollow refractory centers in its lower portion, said centers being supported by the concrete and having tile bottoms, and tension-rods extending through the concrete between the centers, the concrete forming a compression member.
2. In fireproof floor construction, an arch composed of concrete containing hollow refractory centers in its lower portion, said centers being supported by the concrete and having bases extending to the ceiling below, and tension-rods extending through the concrete between the centers, the concrete forming a compression member.
3. In fireproof floor construction, an arch composed of concrete containing hollow refractory centers in its lower portion, said centers being supported by the concrete and the bases of the centers extending to the ceiling below and having flanges *b* constituting the bases of the intervening concrete-filled spaces, and tension-rods extending through the con-

crete between the centers, the concrete forming a compression member.

4. In fireproof floor construction, an arch composed of concrete containing hollow refractory centers in its lower portion, said centers being supported by the concrete and having tile bottoms, tension-rods extending through the concrete between the centers, the concrete forming a compression member, and ceiling-tiles at the bottom of said structure.

5. In fireproof floor construction, an arch composed of concrete containing hollow refractory centers in its lower portion, said centers being supported by the concrete and having tile bottoms, and a tension-rod for each arch extending through each of the concrete fillings between the refractory centers, the concrete structure forming a compression member.

6. In fireproof floor construction, a concrete arch having a permanent refractory center supported by the said concrete, said center having a tile bottom.

7. In fireproof floor construction, a concrete arch having permanent refractory centers supported by the said concrete, the concrete being inclosed at the bottom and sides by extensions from said refractory centers.

In testimony whereof I have hereunto set my hand.

CHARLES F. BUENTE.
